FLAT BED TRAVELING CYLINDER WEB PRINTING PRESS

Edmund W. Dean, Battle Creek, Mich., assignor to Duplex Printing Press Company, Battle Creek, Mich., a corporation of Michigan

Application July 13, 1932, Serial No. 622,340

4 Claims. (Cl. 101—190)

This invention relates to flat bed traveling cylinder web perfecting presses, and its object is to provide a simple means whereby such presses can be used to print four pages of web in two colors if desired, or to print eight pages of web in one color.

Heretofore presses of this type have been adapted to produce a small paper in two colors or a larger paper in one color, as shown for example in Bechman Patents Nos. 708,012 and 708,013. These presses require either divisions in the fountains; or cleaning the fountains and replacing the ink each time colored ink is used, as the same fountain is used for both black or colored ink as desired.

My invention allows the publisher of a small paper to issue a paper at times using color, either to attract attention to some particular feature or merely as an ornamental feature, without this loss of time and the corresponding expense; and it consists in brief in providing an extra (auxiliary) fountain over the usual fountain with mechanism to shift the position of the doctor roll on the crosshead so that it can transfer ink from either fountain to the rolls carrying ink to the forms.

I will explain the invention with reference to the accompanying drawings which illustrate one practical embodiment thereof as applied to one of the so-called "Duplex" flat bed web perfecting presses and summarize in the claims the novel features and combinations of parts for which protection is desired.

In said drawings:

Fig. 1 is a diagrammatic side elevation of a "Duplex" flat web perfecting press with my color printing attachments applied thereto.

Fig. 2 is a top plan view indicating the lead of the web when printing in color.

Fig. 3 is an enlarged detail view of the upper ink fountains; and the adjustable doctor roller mounting.

The press shown has upper and lower type beds 1 and 2 with which cooperate traveling impression cylinders 1a and 2a which are journaled in reciprocating crossheads 3 which are operated by pitman 3a connected to crank wheels 3b mounted on a transverse shaft 3c adjacent the feed and delivery end of the press, as customary in

this type of perfecting press which is ordinarily adapted to print a four page wide web in one color. The web is supplied from a roll W at one end of the press and when printing a four page wide web in one color is led from the roll W to

and over guide rollers b, c, d, to and around a

looping roller e, thence over a guide f on the crosshead 3 beside cylinder 1a, then under cylinder 1a up over a guide g on the crossheads beside cylinder 1a, then under a stationary guide h up over a stationary guide i back over a guide j on the crossheads beside cylinder 2a, then under said cylinder up over another guide k on the crossheads back to and over an upper looping roller e', then over guides m, n, o. Then the web is slit longitudinally, one longitudinal half passing direct to the guide roller x (Fig. 2) at the top of the folder former 8, and the other half being deflected over angle bar p to a guide roll q back to and over a second angle bar r into line with the first half and passes therewith over roller x to the folder.

As the cylinders are rolled back and forth over the beds the web is printed on one side by cylinder 1a from type or printing surfaces on bed 1, and is perfected on its opposite side by cylinder 2a from type on bed 2. The crossheads carry a set of form inking and distributing rollers 4 and doctor 4a (see Fig. 3) beside cylinder 1a to supply ink to the forms on bed 1, and a similar set of inking rollers 5 and doctor 5a beside cylinder 2a to supply ink to the forms on bed 2. Doctor 4a takes ink from an ink fountain 6 at the outer end of the press, and doctor 5a takes ink from a similar fountain 6a above fountain 6, the doctors taking ink from the fountain rolls 85 when the cylinders are at the end of their outward movement. The web is fed forward over the beds intermediate the taking of impressions as in the aforesaid "Duplex" press.

Thus far the parts are all arranged and operated substantially as in the ordinary "Duplex flat bed web perfecting press", such for example as shown in Bechman Patent No. 811,121. The press so far described is capacitated to print a four page wide web in one color on each bed 95 producing a perfected eight page paper in one color.

To enable the press to print a smaller paper in two colors, I provide an auxiliary or third ink fountain 6b preferably mounted above fountain 6a, and supported on standards 6c attached to the press frame, with its fountain roll in position to be contacted by the doctor 5a when the latter is properly adjusted as hereinafter described. The doctor 5a is mounted in vertically adjustable supports 5x (see Fig. 3) each provided with a substantially vertical slot 5b transfixed by a bolt 5c tapped into the side of the crosshead and having a finger 5d transfixed by an adjusting bolt 5e engaging the outer edge 110

of the crosshead, and the support has a projection 5f engaged by an adjusting bolt 5g tapped through a stud 5h on the crosshead. By loosening bolt 5c and adjusting bolts 5d and 5e the ductor 5a can be adjusted approximately vertically on the crosshead so that in lower position the ductor will take ink from the roll of fountain 6a as indicated in dotted lines in Fig. 3, and when adjusted to upper position 10 will take ink from the roll of fountain 6b and also retain contact with distributing roll 5. For convenience of construction the fountain 6b has an undershot roll, while fountains 6 and 6a have overshot rolls. This is to lessen the vertical adjustment of ductor 5a. In its lower position it takes ink on its underside from the upper-side of the roll of fountain 6a, and in its upper position it takes ink on its upper side from the underside of the roll of fountain 6b.

20 The fountains 6 and 6a customarily contain black ink and when a full width (4 pages wide) web is used the ink is supplied from fountains 6, 6a and an eight page paper is produced. When it is desired to print in two colors, for instance 25 black on lower bed and red on the upper bed, a two page wide web is used and only four page papers are produced. The full width web cannot be printed in two colors, as when color is used the narrow web has to pass through the printing 30 mechanism twice, once for each color, and is printed in only one color on each bed, as say red on upper bed and black on lower bed.

When printing a narrow web in two colors, the color, say, red, would be placed in fountain 6b. 35 The web is then led from a half width (two pages wide) web roll at W, and through the press on say the right hand side thereof, in the manner above described as far as the web guide o. In this passage pages two and three are printed in 40 black on one side of the web by cylinder 1a and bed 1, and pages one and four are printed in red on the opposite side of the web by cylinder 2a and bed 2.

Thus far the lead of the web is identical with 45 that of the four page wide web in regular one color printing, the only difference being that the web is two pages wide instead of four.

In order to then print black on pages 1 and 4 and red on pages 2 and 3, it is necessary to pass 50 the web through the printing mechanism again, and, as the black and red colors are to be printed from the same fountains and by same bed and cylinder as before, it is necessary to deflect the web. This is done by leading the narrow web 55 from roll over the angle bar p around guide q to and over the other angle bar r, to guide roller s, which displaces the web to the left hand side of the press, but instead of passing thence to roller x the web is lead from roll s to compensator 60 guide rolls t, thence over guides u, v, to guide c, and from this guide c on through the press to guide roll o the path of the web is identical with the first passage except it is laterally displaced. Pages 2 and 3 having been previously printed in 65 black on the lower type bed are again printed in red on the upper type bed; and pages 1 and 4 having been previously printed in red on the upper bed are again printed in black on the lower type bed during this second passage of the web 70 through the printing mechanism.

The main fountains of the press, if both filled with black ink, would print black on both sides of the paper of a 2, 4, 6 or 8 page newspaper. If two colors are to be printed, usually black and 75 red, the press will print as a maximum only half

the width of the paper, in other words a 2 or 4 page paper. Now, if it is desired to print a 4 page paper, black and red on both sides of the web, black ink is used in the bottom fountain, (the fountain on the bottom deck) and red ink in the auxiliary fountain, and the main or lower fountain of the top deck will not be used, in other words the upper black fountain can remain full of black ink which may have been used the day before and may be used the day after after the color run is wanted. As the paper passes from the supply roll to the bottom deck pages 2 and 3 will be printed in black; as it continues through the upper deck pages 1 and 4 will be printed in red; the paper then goes to the angle bars and guide rolls which deflect the paper and guide it into the press again parallel with the first run and as it passes through the press the second time pages 1 and 4 will have black ink printed on them on the lower deck and pages 2 and 3 will be printed in red ink on the upper deck thus giving red and black on all pages of a four page paper, suitable forms or printing surfaces being placed on the beds from which the proper impressions can be taken.

100 The usual call for color printing in this class of work is to put a red scare head or sub title on the title page and embellish the advertising pages with red ink or sometimes other colors.

The lead of the web is indicated clearly in Fig. 2, the portion of the web in its second passage through the press lying parallel with the portion of the web in taking its first passage through the press. After the web has reached the guide roll o the second time it is taken over 110 guide roll w and led directly to the drag roll x on top of the former and then down the former 8 to the folder, where the product is folded and delivered in the usual manner. This combination of web lead and auxiliary fountain will 115 print four pages in black and color. If for any reason this sequence of printing is not wanted, the fountains may be divided or blocked, using color and black in either or both fountains as described in the Bechman patents above men- 120 tioned.

If desired a press could be built or provided with supplemental color fountain like fountain 6b above the lower fountain 6 and make ductor 4a adjustable like ductor 5a, so that color could 125 be printed on either the upper or lower bed.

I claim:-

1. In a flat bed traveling cylinder printing press having ink distributing rollers, a ductor traveling with the cylinder and a stationary ink 130 fountain; a color fountain arranged parallel with and above the said ink fountain; and means for adjusting the ductor so that it will feed ink from either fountain while remaining in contact with one of the ink distributing rollers. 135

2. In a printing press having a stationary bed, a reciprocating cylinder, an ink fountain at the end of the bed, and ink distributing rollers and a ductor reciprocating with the cylinder; an auxiliary ink fountain arranged parallel with and above the first ink fountain; and means for adjusting the said ductor so that it will take ink from the upper side of the first mentioned ink fountain roll or from the underside of the auxiliary ink fountain roll. 140

3. In a printing press having a stationary bed, a reciprocating crosshead, a cylinder mounted in the crosshead, and an ink fountain at the end of the bed; an auxiliary ink fountain arranged parallel with and above the first ink 145

fountain, a ductor, a vertically adjustable ductor support attached to the crosshead, means for adjusting the support so that the ductor can take ink from the first mentioned ink fountain or from the auxiliary fountain; and means for directing web through the press.

4. In a printing press having a stationary bed, a reciprocating crosshead, a cylinder and inking rollers on the crosshead, and an ink fountain at the end of the bed; an auxiliary ink

fountain arranged parallel with and above the first ink fountain; a ductor, a ductor support attached to the crosshead, means for vertically adjusting the support so that the ductor will take ink from the first mentioned ink fountain or from the auxiliary fountain; and means for directing a full width web once through the press or directing a narrow web twice through the

10 press.
